US00D505729S

(12) **United States Design Patent** (10) Patent No.: **US D505,729 S**
Lee et al. (45) Date of Patent: **** May 31, 2005**

(54) **SLOPE ELECTROPHORESIS**

(75) Inventors: **Jane Q. Lee**, Olathe, KS (US); **John H. Lee**, Olathe, KS (US)

(73) Assignee: **Rigel Technology Corporation**, Shawnee, KS (US)

(**) Term: **14 Years**

(21) Appl. No.: **29/192,598**

(22) Filed: **Oct. 27, 2003**

(51) LOC (7) Cl. **24-01**

(52) U.S. Cl. **D24/233**

(58) Field of Search D24/233, 216,
D24/232; 204/618, 616, 619, 606, 467,
621
